UNITED STATES PATENT OFFICE.

ANTOINE LEFEBURE, OF SAN FRANCISCO, CALIFORNIA.

PLAYING CARDS.

Application filed February 24, 1926. Serial No. 90,370.

This invention relates to playing cards. It is well known that even experienced card players sometimes fail to distinguish between suits of the same color, and therefore 5 make errors in playing. This is due to the fact that suits of the same color, and particularly spades and clubs, consist of symbols which are comparatively not greatly different from each other in configuration 10 and are of about the same visibility. An object of my invention is the provision of playing cards in which suits of the same color may be readily distinguished from each other.

15 With the foregoing object in view, together with such other objects and advantages as may subsequently appear, this invention resides in the construction and arrangement of parts hereinafter described and claimed, and 20 illustrated in the accompanying drawing, in which:

Figure 1 is a view of a group of playing cards showing the four different suits, two of which, namely clubs and diamonds, are 25 according to my invention, while the other two suits, namely spades and hearts, are according to well established construction;

Figure 2 is a view of the ace of clubs in accordance with my invention; and

30 Figure 3 is a view of the ace of diamonds in accordance with the invention.

According to my invention, the suits of a given color may be readily distinguished from each other by changing the symbols 35 of the cards of only one of the suits of that color, leaving the cards of the other suit of the same color unaltered. For example, as illustrated, the symbols of the cards of the spade suit may be printed in solid black as 40 usual, while the symbols of the cards of the club suit, as shown, are printed in solid black around three circular white areas which are located within the confines of the branches of the symbols of the "club" cards.

It will thus be seen that the club suit has a lower visibility than the spade suit, and 45 may be very readily distinguished therefrom.

The symbols of the cards of the heart suit may be printed in solid red as usual, while the cards of the diamond suit, as shown, have their symbols printed around diamond 50 shaped white areas which are located within the confines of the "diamond" symbols and conform in configuration with the complete "diamond" symbols. This construction gives the diamond suit a lower degree of visibility 55 than the usual construction of the heart suit, and enables the two suits to be readily distinguished.

It thus will be obvious that the club suit and the diamond suit will be instantly and 60 unmistakably distinguishable visually from the spade suit and the heart suit, respectively, when a deck of playing cards is formed according to the present invention.

While I have described one embodiment of 65 my invention, modifications thereof may be readily devised without departing from the spirit of my invention, and it is to be understood that such modifications come within the scope of the appended claim. 70

I claim:

Playing cards comprising four suits, the cards of the respective suits being distinguished from one another by colored symbols produced on the faces of the cards 75 and being known as "heart," "diamond," "spade," and "club" cards, respectively, the "diamond" cards having within the confines of certain of their "diamond" symbols substantially white spaces corresponding in 80 configuration with the complete "diamond" symbols, and certain of the symbols of the "club" cards having three substantially white spaces within the confines of the respective branches of said "club" symbols.
